TOILET TISSUE HOLDER

Arthur E. Bauman, 764 Johnston St.,
Akron, Ohio 44306

Filed Nov. 1, 1973, Ser. No. 411,903

Term of patent 14 years

Int. Cl. D23—02

U.S. Cl. D6—97

FIG. 1 is a perspective view of a toilet tissue holder showing my new design.

FIG. 2 is a second embodiment of the design of FIG. 1. The undisclosed rear sides of the toilet tissue holder are flat and unornamented.

I claim:

The ornamental design for a toilet tissue holder, substantially as shown and described.
